J. W. HOPE

CLAMP THUMB TACK

Filed Oct. 3, 1922

INVENTOR.
John W. Hope

Paul Purchard,
Attorneys.

UNITED STATES PATENT OFFICE.

JOHN W. HOPE, OF PITTSBURGH, PENNSYLVANIA.

CLAMP THUMB TACK.

Application filed October 3, 1922. Serial No. 592,131.

To all whom it may concern:

Be it known that I, JOHN W. HOPE, a citizen of the United States, residing at Pittsburgh, in the county of Allegheny and

5 State of Pennsylvania, have invented certain new and useful Improvements in Clamp Thumb Tacks, of which the following is a specification.

This invention relates to clamp thumb tacks and has particular reference to the improved construction of thumb tacks of the type used for holding paper or tracing cloth on the drawing board, or for holding down price tags, such as used in grocery and other 15 stores.

The principle object of this invention is to provide a clamp thumb tack, which does not pierce a hole through the material, when tacked to a drawing board or shelves.

20 Another important feature of my invention provides means for removing the material quickly without the use of tools or knives or, as is generally done, the finger nails, causing the latter to break.

25 Another object of my invention is to design a clamp thumb tack with such regard to proportion and arrangement of parts that it will embody the essential features of simplicity, durability and efficiency, and also 30 relatively low cost of manufacture.

The above and other incidental objects of a similar nature, which will be hereinafter more specifically treated, are accomplished by such means as are illustrated in the accompanying drawings, described in the following specification, and then more particularly pointed out in the claims, which are appended hereto and form part of the application.

40 Referring now to the drawings, wherein there has been illustrated the preferred embodiment of this invention as it is reduced to practice, and throughout the several views of which similar reference characters designate corresponding parts,

45 Figure 1 is a perspective view of the invention.

Figure 2 is a side elevation of the device in open position.

50 Figure 3 is a cross-sectional view on line 3—3, Fig. 5.

Figure 4 is a front elevation of the invention in clamped position.

Figure 5 is a similar view in open position.

Figure 6 is a side elevation of the clamping lever.

Figure 7 is a top elevation thereof.

Figure 8 is a developed plan view of the yoke.

Figure 9 is a side elevation of the same.

Figure 10 is a side view of the spring.

Figure 11 is a bottom view thereof.

Figure 12 is a sectional side elevation, same as Figure 3, but in clamped position.

In the embodiment of the invention illustrated in the accompanying drawings, the clamp thumb tack includes a body-yoke 1, a clamping member 2 and a spring 3.

The body-yoke 1 is preferably formed from sheet material and is substantially rectangular in shape, when in developed form (see Figures 8 and 9). This member is bent over itself to form two relatively long parallel arms 4 and 5, leaving a space 6 therebetween.

Shaped integrally with the yoke 1, is a downwardly disposed pointed projection 7, which serves the same purpose as the commonly known thumb tack.

The upper arm 4 of the body-yoke 1, at the front end, is provided with a substantially rectangular opening 8, and the long sides of said opening are provided with oppositely arranged depressed ears 9, in which is pivotally supported the clamping lever 2, in a manner which will be clearly apparent when reference is had to either Figure 6 or 7.

This clamping lever 2, consists of a flat piece of material, having a pair of oppositely disposed pinlike extensions 10, which are preferably formed integrally with the handle part 11, which is relatively wider at the gripping part.

The forward portion 13 adjacent the pinlike extensions 10, is bent downwardly for a purpose later described.

Referring now to Figures 10 and 11, the spring member 3, consists of a flat, flexible piece of material, bent over itself, to form an upper arm 14 and a lower arm 15; this

lower arm is tapered, as indicated by the numeral 16, and terminates into a downwardly projecting extension 17, of slightly less width, than the opening 7^a in the body-yoke 1.

With reference to Figures 3 and 12, the spring 3 is inserted between the parallel arms 4 and 5, with its closed end adjacent to the closed end of the body-yoke 1, and the downward projection 17 slightly entering the triangular opening 7^a, which thereby prevents the spring from being displaced. Between the pair of ears 9, the clamping member 2 is pivotally inserted in such manner that the pinlike extensions 10 come to lie in the ears 9 and the camlike extension 13 of the clamping member 2 bears against the upper arm 14 of the spring member 3, which has the tendency to normally open up, in a manner as shown in Figure 3.

From the foregoing description, it will be apparent that, when using the clamp thumb tack, the clamping lever should be in closed position, so that the thumb may be used for pushing the clamp thumb tack into the board in the same manner as the commonly known thumb tacks; the clamping lever is now opened, the paper inserted between the two arms of the spring member 3 and by pushing the clamping lever downwardly the parallel arms of said spring are brought together and due to the pressure exerted the paper or cloth is held rigidly. The same method is employed when the device is used for price tags in grocery stores, etc.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desirable to emphasize the fact that various minor changes in details of construction, proportion and arrangement of parts may be resorted to, when re-

quired, without sacrificing any of the advantages of this invention as defined in the appended claims.

I claim as new:

1. A clamp thumb tack comprising a substantially U-shaped yoke member having a depending piercing means formed out of the lower arm of said yoke; a normally outwardly flaring U-shaped spring member positioned within the bight of said yoke member and having a downwardly directed projection engaging the aperture created by the formation of said piercing means; a hingedly mounted clamping lever engaging the upper arm of said yoke member and acting upon said spring member, and means for retaining said clamping lever.

2. A clamp thumb tack comprising a substantially U-shaped yoke member having a depending piercing means formed out of the lower arm of said yoke; a normally outwardly flaring U-shaped spring member positioned within the bight of said yoke member and having a downwardly directed projection engaging the aperture created by the formation of said piercing means; a hingedly mounted clamping lever engaging the upper arm of said yoke and acting upon said spring member, and resilient means for retaining said clamping lever.

3. A clamp thumb tack comprising a substantially U-shaped yoke member having a depending piercing means formed out of the lower arm of said yoke; a normally outwardly flaring U-shaped spring member positioned within the bight of said yoke member and having a downwardly directed projection at the outer end of its lower arm for engagement with the aperture created by the formation of said piercing means; a hingedly mounted clamping lever engaging the upper arm of said yoke and acting upon said spring member; said clamping lever being retained in position by the outward pressure of said spring member.

In testimony whereof I affix my signature.
JOHN W. HOPE.
